(57) CLAIM

The ornamental design for a portion of a golf club head, as shown and described.

DESCRIPTION

FIG. 1 is a bottom perspective view of a portion of a golf club head showing our new design;

FIG. 2 is a bottom view thereof;

FIG. 3 is a toe end view thereof;

FIG. 4 is a heel end view thereof; and,

FIG. 5 is a rear view thereof.

The broken line showing of the fins within the shaded region and the remainder of the golf club head is for illustrative purposes only and forms no part of the claimed design.
